UNITED STATES PATENT OFFICE.

JULIUS F. STONE, OF COLUMBUS, OHIO.

FIRE APPARATUS.

1,241,572.

Specification of Letters Patent.

Patented Oct. 2, 1917.

Application filed December 24, 1915. Serial No. 66,483.

To all whom it may concern:

Be it known that I, JULIUS F. STONE, a citizen of the United States, residing at Columbus, in the county of Franklin and State of Ohio, have invented a certain new and useful Improvement in Fire Apparatus, of which the following is a specification.

This invention relates more particularly to motor fire apparatus which carries a pumping engine and hose and the object of the invention is to simplify the construction whereby an economy of power and space is effected and the apparatus made steadier and more secure from overturning in running.

The invention is embodied in the construction herein shown and described and then particularly claimed.

In the accompanying drawing—
20 Figure 1 is a general view in side elevation.

Fig. 2 is a side elevation on a larger scale of the rear portion of the chassis with the body removed.

25 Fig. 3 is a plan view of what is shown in Fig. 2.

Fig. 4 is a sectional view of the pump and driving gearing associated therewith.

In the views 5 designates the frame of the 30 chassis which is mounted upon the front wheels 6 and rear wheels 7. The vehicle is driven from the rear wheels. At 8 is the hood which incloses the gasolene engine which may be of any approved type. The 35 operator's seat is shown at 9. The steering wheel is designated 12. A gasolene tank 13 can be supported in the usual way in rear of the seat. A hose receptacle 14 is mounted on the frame in rear of the seat and is provided with a step at 15 and a hand rail 16. The 40 step is within convenient reach of the ground and the hose receptacle is easily accessible to firemen standing on the step.

17 designates the main driving or crank 45 shaft which is composed of two parts connected by a separable clutch at 19 as usual. Said shaft extends longitudinally of the car to a transmission and speed changing and reversing gearing designated generally by 50 the character 18. This gearing is of usual or approved construction and needs no particular description here. The clutch 19 is provided with an operating foot lever 20 for disconnecting the parts of the driving shaft when starting, changing speed, reversing or stopping.

Surrounding the main vehicle driving shaft between the clutch 19 and the transmission gearing 18 is a tubular shaft 21 carrying secured thereto impellers 22 of a pump. These impellers work in a stationary pump casing 23 supported by suitable frame members 23^a in the chassis and having intakes 24 and outlets 25. The tubular shaft 21 has suitable antifriction bearings at 26 and 27 in bosses on the stationary pump casing. At its forward end the tubular shaft 21 is provided with a gear wheel 47 which is permanently engaged by a gear wheel 28 fixed to an auxiliary shaft 29 in a suitable 70 casing 30. Keyed on the main driving shaft 17 is a gear wheel 31, and slidingly mounted on a splined portion of the auxiliary shaft 29 is spur gear 32 adapted to be slid into and out of engagement with said gear wheel 75 31. Engaging a groove 32^a in the gear 32 is a sliding fork 33 actuated by a crank arm 34 on one end of a shaft 35 mounted in a bracket 36. The other end of said shaft 35 extends through and beyond the tubular 80 shaft 37 and receives a hand lever 38 so that the gear 32 can be shifted by an operator while standing on the ground at the side of the apparatus. The tubular shaft 37 has connected with it a rod 37^a extending rearward to actuate the speed changing 85 gearing. The hand lever 38 works adjacent a latching sector 38^a of ordinary construction.

The apparatus contains the usual controlling lever for working in the H slot at 39 for operating the gear shifts of the speed changing and reversing gears. When the engine is operating and said lever stands in the "neutral" position and the clutch of the 95 main shaft connects the parts of that shaft, said shaft is rotated but without transmitting power to the tractor wheels. To cause the prompt stopping of the drive shaft without stopping the engine the rear side of 100 the sliding clutch member is provided with a brake member 43 that cooperates when slid rearward with a brake member 44 on the shaft. This construction is usual in motor vehicles for the purpose of permitting the shifting of the speed changing and 105 reversing gears and similarly the arrangement here described permits the shifting of the gear 32 into engagement with the gear 31 for operating the pump.

110 Among the advantages of this construction are that the pump, which is a heavy

structure, is located between the front and rear wheels thereby distributing the load substantially equally on both; the center of gravity of the structure is placed low so that 5 danger of overturning in rounding corners is lessened, space is left in the superstructure for other uses, as for example, for carrying firemen and hose and other equipment useful in extinguishing fires.

- 10 In practice the main shaft clutch is operated, as usual from the driver's seat by the foot lever 20 that actuates a crank arm 41 on a shaft 42, said crank being connected with the sliding clutch member in the usual way.
- 15 In order that the said main shaft clutch member may be disconnected for the purpose of permitting the connection of the propeller shaft with the pump when the operator is standing on the ground, said 20 shaft 42 is extended to the side of the apparatus where it is provided with a lever 45 for disconnecting the sliding member of the main clutch and stopping the operation of that portion of the drive shaft in rear of the 25 clutch.

While I have shown the invention as embodied in a motor fire apparatus it can, of course, be used in other vehicles in which a pump is useful.

30 What I claim is:

1. In a motor vehicle pumping apparatus, the combination with the chassis having main longitudinal frame members, of a motor, main clutch for the vehicle, transmission 35 gearing and propeller shaft disposed between the main clutch and the transmission gearing, a pump casing, transverse frame members supporting the pump casing between the main frame members of the chassis and disposed between the ends of the propeller shaft, bearings supported by the pump casing, a tubular shaft through which the propeller shaft passes journaled rotatably in the bearings, an impeller for the 40 pump carried by the tubular shaft and means for operatively connecting and disconnecting said tubular and propeller shafts.

2. In a motor vehicle pumping apparatus, a chassis having a motor, a transmission 50 gearing, a drive shaft operated by the motor, a shiftable clutch device on said shaft for connecting the transmission with and disconnecting the same from the drive shaft, said clutch being operable from the driver's 55 seat and means whereby said shiftable clutch device may likewise be operated by a person outside the vehicle, a pump having an impeller shaft, shiftable means for operatively connecting and disconnecting said impeller 60 shaft, said shiftable means being operable from the driver's seat and means whereby

the same may be likewise operated by a person outside the vehicle.

3. In a motor vehicle, the combination with the chassis, motor, main clutch for the 65 vehicle change-speed gearing, and propeller shaft interposed between the clutch and the gearing, of a tubular shaft through which the propeller shaft passes loosely, means for mounting the tubular shaft rotatably on the 70 chassis, a pump connected to said tubular shaft, and clutch means between the tubular shaft and the propeller shaft for connecting the shaft to and disconnecting it from the pump at will.

4. The combination with a vehicle chassis, a motor, a main clutch, vehicle driving means, and a propeller shaft, of a clutch device for connecting the propeller shaft with and disconnecting it from the vehicle driving means, a tubular shaft through which the propeller shaft extends and means for mounting the tubular shaft on the chassis, a pump connected with the tubular shaft and 80 clutch means for connecting the tubular shaft with the propeller shaft independently of the vehicle driving means.

5. In a motor vehicle, the combination with the chassis, motor, main clutch for the vehicle, change-speed gearing and propeller 90 shaft interposed between the clutch and the gearing, of transverse frame members supported by the side frame members of the chassis and disposed between the clutch and said gearing, bearings carried by said transverse frame members, a tubular shaft mounted rotatably in said bearings and 95 through which the propeller shaft extends loosely, a pump carried on the frame members and connected operatively to the tubular shaft, and clutch elements disposed between the tubular shaft and the propeller shaft.

6. In a motor vehicle, the combination with the chassis, motor, main clutch for the 105 vehicle, change-speed gearing, a propeller shaft disposed between the main clutch and the gearing, of transverse frame members extending between the main frame members of the chassis and located between the ends 110 of the propeller shaft, bearings carried by the transverse frame members, a tubular shaft mounted rotatably in the bearings and through which the propeller shaft extends loosely, a pump casing carried on the transverse frame members; a rotor for the pump carried by the tubular shaft, and independent clutch devices operatively interposed between the propeller shaft and the tubular shaft.

JULIUS F. STONE.
